DESIGN FOR A DRESS ENSEMBLE

Louis Katz, New York, N. Y.

Application May 8, 1939, Serial No. 84,854

Term of patent 3½ years

To all whom it may concern:

Be it known that I, Louis Katz, a citizen of the United States, residing in New York city, in the county of New York and State of New York, have invented a new, original, and ornamental Design for a Dress Ensemble, of which the following is a specification, reference being had to the accompanying drawing, forming part thereof.

Fig. 1 is a front view of a dress ensemble showing my design;

Fig. 2 is a rear view of Fig. 1,

Fig. 3 is a front view of the dress member of the ensemble shown in Figs. 1 and 2, and
Fig. 4 is a rear view thereof.

The characteristic feature of my design resides in the combination on the specific ensemble disclosed of the specific bands of eyelet embroidery arranged in the manner and position shown.

I claim:

The ornamental design for a dress ensemble, substantially as shown and described.

LOUIS KATZ.
